C. B. HEIM.

PAPER PRESS.

APPLICATION FILED JAN. 19, 1914.

1,113,625.

Patented Oct. 13, 1914.

UNITED STATES PATENT OFFICE.

CHARLES B. HEIM, OF MARCO, INDIANA.

PAPER-PRESS.

1,113,625.

Specification of Letters Patent.

Patented Oct. 13, 1914.

Application filed January 19, 1914. Serial No. 813,031.

To all whom it may concern:

Be it known that I, CHARLES B. HEIM, a citizen of the United States, and a resident of Marco, county of Greene, and State of Indiana, have invented a certain new and useful Paper-Press; and I do hereby declare that the following is a full, clear, and exact description thereof, reference being had to the accompanying drawings, in which like letters refer to like parts.

The object of this invention is to simplify the construction of baling presses of the type suitable for baling old waste papers and the like and to render the same convenient and easy of operation. Paper presses of this type are used by collectors of waste papers and, therefore, simplicity in construction and ease of operation are of very great importance as the purchasers and users of such devices are not financially able or provided with mechanical help or with sufficient business to justify the use of complex or large expensive baling mechanism.

One feature of the invention consists in a simple loop-like means for mounting and holding the screw beam when in use and also when not in use.

The full nature of the invention will be understood from the accompanying drawings and the following description and claims.

In the drawings, Figure 1 is a perspective view of the paper press closed and in operation. Fig. 2 is the same after the bale has been formed and with the parts in position for the removal of the bale and the subsequent introduction of more paper, parts being broken away. Fig. 3 is a section on the line 3—3 of Fig. 2.

There is shown herein a rectangular press box open at the top and with sides 3, a back 4, a bottom 5, a door 6 and top bar 7 located immediately above the door when it is closed. The bottom 5 has grooves 8 therein for the insertion of baling wires 9 for baling the bale 10 of waste paper.

The door 6 is hinged to the bottom of the box by the hinges 11 so that the door can be opened outwardly and downwardly and when lying on the floor or ground, the hinged end 50 of the door will be flush with the upper surface of the bottom 5 of the press box. This always maintains the door in the proper position with reference to the press box, when the door is open, and the proper relation of 55 the door to the bottom of the press box is also maintained. This facilitates the re-

moval of the bale 10 from the bale box by throwing it out of the bale box upon the door 6 which for the time being is a platform. After the bale is removed the door is up-ended or closed with the upper end fitting immediately under the cross bar 7 and it is secured in closed position by latches 12 on the box engaging pins 13 extending laterally from the door. The latches 12 have notches 14 in their under sides for engaging the pin and have outwardly bent or extending handles 15 for operating the latches.

When the door is closed, the device becomes a waste paper box into which waste paper is thrown through the open top, and after it is full of waste paper, a press plate 16 is placed in the upper end of the box upon the papers for pressing the papers down, as shown.

The press plate 16 has grooves 17 for the wires 9 and has one or more handles 18 for its removal and a centrally located metal bearing plate 19 for the end of a screw 20. The screw operates through a screw beam 80 21 and has on its upper end a hollow T-head 22 through which a turning hand bar 23 is loosely and removably inserted, as desired. There is also upon said head 22 a handle 24 projecting upward therefrom to one side of 85 the axis of the screw 20. This handle 24 is for the purpose of operating the screw 20, when not under strain, while the hand bar 23 is for operating the screw while under strain.

When the screw beam 21 lies cross-wise of the top of the press box, it is held in place by a loop 30 at one end and a loop 31 at the other end. These loops are pivotally mounted in connection with the upper end 95 of the press box by pivot plates 32 and the loops extend over and around the ends of the screw beam, as shown in Fig 1, and the loop 30 is pivotally secured to the upper side of the screw beam by a plate 34 so that 100 the screw beam cannot escape from the press box. Beneath the pivot plate 32 for the loop 30 there is a stop block 35 secured to the side of the box for engaging the end portion of the beam 21 and holding it in a semi-elevated position, as shown in Fig 2. This makes it easy to return the screw beam into position on top of the press box after the box is filled with papers and it is desired to press and bale the same.

After the box is full of papers, the press plate 16 is inserted in the upper end of the

box upon the papers. The screw beam 21 is turned from the position shown in Fig. 2 to that shown in Fig. 1 on top of the box, and the loop 31 is caught over the free end 5 of said beam 21 so as to hold said beam in position on the press box. The screw 20 is then run down by the handle 24 until it comes into engagement with the metal plate 19 on the press plate 16. The bar 23 is then 10 inserted in the head of the screw and the screw actuated until the papers is under sufficient pressure. After the bale is finished, the door is unlatched and turned down to form a platform and the wires are 15 inserted from the rear through grooves 17 and then from the front through grooves 8 and tied. Then the screw is released from strain by backward movement of the hand bar 24 and said bar taken out and the screw 20 run up by the handle 24 and then the loop 31 is removed from the free end of the screw beam 21 and said screw beam is thrown back 25 out of the way in the position shown in Fig. 2, where it is maintained in an elevated position by the end of the beam engaging the stop block 35 so that the loop 30 will support the screw beam in such position and out of the way. After the press plate 16 is removed, the bale is moved out of the box 30 upon the platform.

The invention claimed is:

1. A baling press including a box open at

its upper end, a screw beam adapted to lie across the top of the box for receiving a screw for pressing the contents of the box, 35 a loop pivotally secured to one side of the box and pivotally connected with said screw beam near one end so that the screw beam cannot escape therefrom, a loop pivotally secured to the opposite side of the box 40 adapted to be placed over the free end of the beam when it is placed upon the box, and a stop on the side of the box to engage the end of said screw beam when turned up and back for holding the same in an elevated 45 position.

2. A baling press including a box open at its upper end, a screw beam adapted to be placed across the top of the box, a screw operating through said screw beam for 50 pressing the contents of the box and having a socketed head adapted to receive and removably hold a hand bar, and a handle secured on said head projecting upward therefrom and to one side of the axis of the 55 screw for operating said screw when not under strain.

In witness whereof, I have hereunto affixed my signature in the presence of the witnesses herein named.

CHARLES B. HEIM.
